UNITED STATES PATENT OFFICE

WILLIAM A. SMITH, SR., OF EASTON, PENNSYLVANIA, AND WILLIAM A. SMITH, JR., OF PHILLIPSBURG, NEW JERSEY, ASSIGNEES TO INGERSOLL-RAND COMPANY, OF JERSEY CITY, NEW JERSEY, A CORPORATION OF NEW JERSEY

PILE-DRIVER ATTACHMENT FOR ROCK DRILLS

Application filed November 4, 1929. Serial No. 404,801.

This invention relates to pile drivers, but more particularly to a pile driver attachment for rock drills of the hammer type.

One object of the invention is to obtain a rugged and efficient pile driving attachment which may be applied to and removed from the work with a minimum expenditure of time and effort.

Another object is to simplify the construction and reduce the cost of manufacturing of an attachment of this type.

Other objects will be in part obvious and in part pointed out hereinafter.

In the accompanying drawings forming part of the following specification and in which similar reference characters refer to similar parts,

Figure 1 is a sectional elevation of the attachment,

Figure 2 is a side elevation, partly broken away, and

Figure 3 is a transverse view taken through Figure 1 on the line 3—3 looking in the direction indicated by the arrows.

Referring to the drawings, the invention is shown applied to a fluid actuated rock drill, only a portion of the cylinder A and the hammer piston B therein being shown.

In accordance with the present invention, the rock drill is provided with a driving attachment designated generally by C and which may be suitably clamped in the assembled position with respect to the cylinder A by means of side bolts D. The attachment C comprises a pair of symmetrical members or half-sections E having lugs F at the rearward ends through which the bolts D extend. The members E may be clamped securely together in face to face relationship by any suitable means as for instance by bolts G.

In the contiguous surfaces of the members E are rectangular grooves H which register with each other to form a rectangular bore J in the attachment C. In the rearward end of the attachment is a cavity K which may be of substantially the same diameter as the cylinder, and in the side walls of the grooves H are formed passages L which communicate with atmospheric vents O to convey from the front end of the cylinder any compres-

sion which may be created by the piston and which would otherwise cushion the forward stroke of the said piston.

At the forward ends of the members E are integral extensions P which are suitably spaced with respect to each other to form therebetween a slot Q for the reception of the end of a pile R. The extensions P may be so spaced that the slot Q will be of a width capable of receiving piles of considerable thickness. When used, however, for driving piles of relatively small width cheek plates S may be secured to the inner surfaces of the extensions as by means of bolts T to reduce the width of the slot Q.

The cheek plates S may vary in width in accordance with the thickness of the piles intended to be driven and in order to protect the bolts T against the effects of such blows of the striking block as may be delivered against the cheek plates, said cheek plates may be provided with tongues U which seat in grooves V in the inner surfaces of the extensions P.

An additional function of the cheek plates S is to act as a stop for a striking block W which is preferably of rectangular shape and is disposed in the rearward end of the slot Q to transmit the blows of the hammer piston B to the pile R. The striking block W may be provided with the usual pointers X for engagement with the pile R and has a rectangular stem Y which extends slidably through the rectangular grooves H and into the cavity K to receive the blows of the hammer piston B.

In order that the cooperating surfaces of the rectangular bore J and the stem Y of the striking block may at all times be suitably lubricated the members E are provided with grooves Z which extend from the cavity K along the wall of the bore J to a point well toward the forward end of the said bore J. In this way a portion of the lubricant entrained by the pressure fluid utilized for actuating the piston B will be deposited in the grooves Z for lubricating the stem Y.

We claim:

1. The combination with a fluid actuated rock drill having a cylinder and a hammer

piston in the cylinder, of a front head having a rectangular bore therethrough, extensions on the front head spaced with respect to each other to form a slot for the reception of a pile, a striking block in the slot, and a rectangular stem on the striking block slidable in the bore and extending rearwardly thereof to receive the blows of the hammer piston.

2. The combination with a fluid actuated rock drill having a cylinder and a hammer piston in the cylinder, of a front head comprising a pair of half-sections, each having a longitudinal groove in their contiguous surfaces to form a bore, extensions on the half-sections spaced with respect to each other to form a slot for the reception of the end of a pile, a striking block in the slot, and a stem on the striking block and extending through the bore to receive the blows of the hammer piston.

3. The combination with a fluid actuated rock drill having a cylinder and a hammer piston therein, of a front head having a rectangular bore and a cavity at the rearward end of the bore, integral extensions on the front head spaced with respect to each other to form a slot for the reception of the end of a pile, a striking block in the slot, a rectangular stem on the striking block slidable in the bore and extending into the cavity to receive the blows of the hammer piston, and a passage in the front head to convey compression from the cavity to the atmosphere.

4. The combination with a fluid actuated rock drill having a cylinder and a hammer piston in the cylinder, of a pair of symmetrical members disposed in face to face relationship to form a front head, rectangular grooves in the adjacent surfaces of the members and in registry with each other to form a rectangular bore, means for clamping the members together, extensions on the members spaced to form a slot therebetween, a striking block in the slot, and a rectangular stem on the striking block and extending through the bore to receive the blows of the hammer piston.

5. In testimony whereof we have signed this specification.
